G. J. GIANNACOPOULOS.
 BRIDGING DEVICE FOR RAILWAY CROSSINGS.
 APPLICATION FILED OCT. 19, 1917.

1,259,729.

Patented Mar. 19, 1918.

UNITED STATES PATENT OFFICE.

GEORGE J. GIANNACOPOULOS, OF PITTSBURGH, PENNSYLVANIA.

BRIDGING DEVICE FOR RAILWAY-CROSSINGS.

1,259,729.

Specification of Letters Patent. Patented Mar. 19, 1918.

Application filed October 19, 1917. Serial No. 197,433.

To all whom it may concern:

Be it known that I, GEORGE J. GIANNACOPOULOS, a subject of the King of Greece, who has procured preliminary naturalization 5 papers of the United States, residing at Pittsburgh, county of Allegheny, and State of Pennsylvania, have invented certain new and useful Improvements in Bridging Devices for Railway-Crossings, of which the 10 following is a specification.

This invention relates to car-actuated bridging devices for railway crossings.

My invention relates to that general class 15 of bridging devices used at railway crossings for the purpose of automatically closing or bridging the slot or space between the rail ends, when a car goes over the crossing, the purpose being to afford a continuous rail, as it were, on which the wheels will travel and 20 thereby avoid the shock and noise incident to passage of the wheels over the open space.

My invention contemplates the provision of a spring-retracted bridging member, a compressible abutment carried thereby against 25 which the car wheel abuts so that the bridging member will be automatically shifted as the car goes over the crossing, and improved latching means for the abutment.

A further object is the provision in a 30 device of the character set forth, of improved means whereby the bridging member may be manually set to bridge the space between the rail ends when a car is backing toward the crossing.

The embodiments of the invention which 35 are hereinafter set forth and shown in the accompanying drawings, are to be considered as merely illustrative of the invention and not in limitation of its scope, as modifications may be resorted to.

In the accompanying drawings,

Figure 1 is a plan view of a part of a railway crossing equipped with my improvements.

Fig. 2 is a detail longitudinal section of the invention taken on the line 2--2 of Fig. 1.

Fig. 3 is a cross section on the line 3--3 of Fig. 1.

Fig. 4 is a horizontal section on the line 50 4--4 of Fig. 2.

Fig. 5 is a detail side view of the bridging member.

Fig. 6 is a detail of the abutment, and

Fig. 7 is a detail of the latching device.

55 The ends of one rail of a crossing are shown at 1 and those of the other part at 2.

At each of the four points where the rails cross, at a crossing, there would be provided an arrangement such as shown in Fig. 1 so that the rail ends will be bridged regardless of which track is used and the direction of travel.

Suitable castings may be used where the rails cross or, the rail ends themselves may be formed with concavities and slots to accommodate the present improvement. Slidable in a cavity 3 in the rail end is a bridging member 4 which may be provided with a roller 5 to lessen friction. The bridging member 4 is retracted by suitable springs 6 60 which may be secured by a bolt 7 and a plate 8 and contained within a cavity 5^a, the latter having a suitable cover 9 which may be opened to give access to the cavity 5^a. Any suitable buffer spring 10, contained with 65 the cavity 5^a, serves to cushion the return of the bridging member 4 when it has been retracted by the springs 6 after its release from actuation by the car.

Slidable vertically in the bridging member 4 is an abutment 11 which is preferably provided with an inclined upper face 12 so that the car wheel may readily ride thereover when said abutment 11 is released. The abutment 11, which is shown in detail in Fig. 6, 80 has a head 13 which prevents it from being pulled out of the bridging member 4. It is also provided with a reduced portion 14. A spring 15 in a cavity 16 forces the abutment 11 upwardly until the head 13 strikes 85 the end of the cavity. A removable closure 17 is arranged at the bottom of the cavity 16. Slidable horizontally in a slot 18 in the member 4 is a latch 19 which is pressed by a spring 20 and has a bifurcated end portion comprising a narrow part 21 and a wider part 22 which have shoulders 23. When the latching member 19 is in the position shown in Fig. 2, the shoulders 23 engage the shoulders of the reduced part 14 90 thereby locking the abutment 11 so that it cannot be pressed downwardly. This is the normal position of the parts. The end of the latching member 19 projects beyond the end of the bridging member 4 as shown at 95 24. Consequently when the bridging member has been moved forwardly to nearly the end of the cavity 3, the projecting end 24 engages the wall 3^a and pushes the latching member 19 inwardly against spring 20, thereby 100 disengaging the shoulder 23 from the part 14. The car wheel then depresses the

105 24. Consequently when the bridging member has been moved forwardly to nearly the end of the cavity 3, the projecting end 24 engages the wall 3^a and pushes the latching member 19 inwardly against spring 20, thereby 110 disengaging the shoulder 23 from the part 14. The car wheel then depresses the

abutment 11 and when the car has passed the crossing, the member is retracted by the springs 6. The cushion spring 10 cushions the return of the member 4.

5 To enable the bridging member to be set to bridge the space between the rail ends when a car is backing over a crossing, I provide the devices shown in Figs. 3 and 5 comprising a rack 25 on the member 4, a pinion 26 on a shaft 27 mounted in a removable plate 28 and provided with a bevel gear 29. Journaled in a bracket 30 on the side of the rail is a shaft 31 which has a squared end 32 adapted to be engaged by a suitable crank 15 or handle. Any preferred means may be employed for locking the shaft 31 after the member 4 has been advanced until it strikes the wall 3^a. One such device is that shown, comprising a toothed wheel 33 on the shaft 31, and a removable locking pin or bolt 34 which can be introduced through an opening 35 in the top of the casing 36 which is employed to house the parts. The same casing 36 may be used for the two bridging devices 25 on two different rails as shown in Fig. 1; said casing is removable. Having turned the shaft 31 to advance the bridging member 4 until it strikes the wall 3^a, the latching member 19 is thereby released and consequently the abutment 11 will be depressed by the car wheel. The pin 34 holds the abutment member in position and can be removed after the car has passed to permit the parts to resume the position in Fig. 2.

35 Having thus described my invention, what I claim and desire to secure by Letters Patent, is:

1. In a bridging device for crossings, the combination with a movable spring-retracted bridging member, of a depressible abutment carried thereby positioned to be engaged by the wheel of a car going over the crossing, and means for normally locking said depressible abutment, adapted to be released, 40 to permit depression of the abutment, when the bridging member has been moved to bridging position.

2. In a bridging device for crossings, the combination with a movable spring-retracted

bridging member, of a depressible abutment 50 carried thereby, spring means for keeping said abutment normally elevated, and a spring-actuated locking device for the abutment which is arranged to be released from the abutment when the bridging member has 55 assumed bridging position.

3. In a bridging device for crossings, the combination with a slidable bridging member, of coil springs for holding said member normally retracted, a cushioning device for 60 said bridging member when the latter is in retracted position, an upwardly spring-pressed abutment carried by the bridging member, and a horizontally slidable spring-actuated latch adapted to normally engage 65 the abutment to lock it against depression, said latch having a projecting part adapted to be engaged by a part of the rail when the bridging member has assumed bridging position, to thereby release the latch from the 70 abutment so that the latter may be depressed by the wheel of the car going over the crossing.

4. In a bridging device for crossings, the combination with a movable bridging member adapted to be engaged by the wheel of a car going over the crossing to thereby arrange said member in bridging position, and manually operable means, adapted for operation independently of the car-actuation 80 of the bridging member, whereby said bridging member may be arranged in bridging position.

5. In a bridging device for crossings, the combination with a movable bridging member 85 adapted to be engaged by the wheel of a car going over the crossing to thereby arrange said member in bridging position, and independent means for manually arranging the bridging member in bridging 90 position comprising a rack on the bridging member, a pinion carried by the rail and engaging the rack, operating means for the pinion, and locking means for said operating means.

95 In testimony whereof, I hereunto affix my signature.

GEORGE J. GIANNACOPOULOS.
